UNITED STATES PATENT OFFICE

MARCEL MENNESSON, OF NEUILLY-ON-THE-SEINE, FRANCE, ASSIGNOR TO "SOCIETE ANONYME SOLEX", OF NEUILLY-ON-THE-SEINE, SEINE, FRANCE, A SOCIETY

CARBURETOR

Application filed September 8, 1931, Serial No. 561,749, and in Belgium June 12, 1931.

The present invention relates to carburetors, and more particularly, to those of the type wherein a small auxiliary carburetor cooperates with the main carburetor assembly during starting and operation with a cold motor.

One of the objects of the invention is to provide a carburetor assembly in which means are provided for preparing the main nozzle for operation as soon as the auxiliary carburetor is cut out.

Another object is to so position the feed orifice communicating with the auxiliary carburetor that the explosive mixture entering the intake manifold is properly distributed to the various cylinders.

Further objects will appear in the course of the detailed description now to be given with reference to the accompanying drawings, in which:

Figure 1 is a section taken on line 1—1 of Figure 2 to be described and showing one illustrative embodiment of the invention;

Figure 2 is a side view of the structure represented in Figure 1;

Figures 3 and 4 are sections showing certain details of the assembly illustrated in Figures 1 and 2 at different phases in the operation thereof;

30 Figure 5 is an elevation of a second form of carburetor constructed in accordance with the invention; and

Figure 6 represents, in plan, the form of carburetor shown in Figure 5.

35 Referring to Figures 1 to 4 of the drawings, there is shown an assembly composed of the following elements: a float 1 mounted in a constant level chamber of conventional construction; a slow speed nozzle 2 supplied with 40 fuel from the constant level chamber via a system of conduits such as those shown in Figure 1; a main nozzle 3 also supplied with fuel from the constant level chamber, this nozzle being of any desired type, but 45 preferably of one such as is represented in Figure 1; an auxiliary mixing chamber 4 positioned above nozzle 2; a main mixing chamber 5 receiving fuel from nozzles 2 and 3; a butterfly or similar type of throttle valve 50 6 mounted so that, in closed position, it com-

pletely closes mixing chamber 4 and covers the greater part of the discharge orifice of mixing chamber 4; and an auxiliary carburetor assembly composed of a fuel supply passage 7 receiving fuel from the constant level chamber, a submerged calibrated orifice 8, a well 9 communicating with the atmosphere at 10, a plug 12 provided with a calibrated orifice 11 positioned to lie under the lever of fuel contained in well 9, a conduit 13 provided with an emulsifying air inlet 14, a mixing chamber 15, a passage 16 communicating at one extremity with main mixing chamber 5 at a point downstreamward with relation to throttle valve 6, the point of communication with mixing chamber 5 being positioned to lie along the axis of symmetry of an intake manifold 36 having branches 37 and 38 each feeding a like number of cylinders, passage 16 being formed so as to be able to communicate with chamber 15 under conditions to be described, a shaft 17 of square or polygonal section rotatably supported in a pair of journals 19 and 20, a lever 18 rigidly attached to shaft 17 and connected to the dash board by any convenient form of transmission (not shown), a cover element 21 provided with a pair of air intake orifices 32 and 33, a plate 22 having a central opening therein of square or polygonal form adapted to fit over the correspondingly shaped portion of shaft 17, plate 22 having a first elongated opening 27 (Figures 3 and 4) formed therein and adapted to control communication between chamber 15 and passage 16 when shaft 17 is rotated, plate 22 being further provided with a circular orifice 28, a passage 29 having one extremity positioned to communicate with mixing chamber 5 at a point upstreamward with relation to throttle valve 6 and having its other extremity positioned to communicate with chamber 15 via orifice 28 in a manner to be described, a second plate 23 also having a square or polygonal central orifice formed therethrough coacting with correspondingly shaped portions of shaft 17, plate 23 having a pair of openings 30 and 31 positioned to move across air intake passages 32 and 33 when shaft 17 is rotated, a machined lateral

surface 24 covering the face of plate 22 and a second machined surface 25 covering the face of plate 23, a spring 26 tending to apply plates 22 and 23 firmly against surfaces 24 and 25, and a plug 35 having an air inlet passage 34 positioned to communicate at opposite extremities with the air and with chamber 15.

The hereinabove described assembly operates in the following manner:

Assuming the motor to be cold and at rest and throttle valve 6 in closed position, that is to say so as to completely block mixing chamber 5 and partially cover the discharge orifice of auxiliary mixing chamber 4 (Figure 1), and that it be desired to start the motor while cold and to maintain the latter in rotation until warm, lever 18 is displaced so as to rotate shaft 17 and bring plates 22 and 23 into the position shown in Figures 1 and 3. Main mixing chamber 5 is then in communication with chamber 15 via passage 16 and orifice 27, while, at the same time, chamber 15 communicates with main chamber 5 downstreamward of throttle valve 6 via passage 28 and orifice 28. At this stage, plate 23 cuts off communication between chamber 15 and air inlet passages 32 and 33, while passage 34 continues to supply air from the atmosphere to said chamber. If the position and dimensions of the various passages and orifices as well as the design of elements 12, 13 and 14 are chosen to give a proper mixture during cold operation and slow speed, the motor will at once start when turned over, the supply of fuel from orifice 8, will be dependent on the fluid pressure transmitted from the constant level chamber and the carburetion will vary automatically in accordance with the changes of speed of the motor resulting from the diminution of its internal resistance (varying viscosity of the oil, etc.). The form, dimensions and position of the various passages communicating with chamber 15 permit regulation of the transition in operation from the auxiliary carburetor assembly to the main carburetor assembly. Inasmuch as chamber 15 communicates via passages 16 and 29 with opposite sides of the throttle valve, it creates a depression in the main mixing chamber tending to maintain principal nozzle 3 ready to supply fuel as soon as the throttle valve is opened. In order to insure a gradual transition, when shaft 17 is rotated to cut out the auxiliary carburetor assembly, air inlets 32 and 33 and orifices 30 and 31 are positioned so as to replace the air formerly entering via passage 29 and orifice 28. As soon as shaft 17 is turned so as to cut off communication at 28-29 and 16-27, the auxiliary carburetor no longer supplies fuel to mixing chamber 5. At that time, passages 30, 32 and 31-33 establish communication between chamber 15 and the atmosphere. If, because of leak-

age, part of the depression in main mixing chamber 5, is transmitted to chamber 15, the opening of passages 30-32 and 31 prevents fuel being fed from conduit 13.

Figure 3 shows, in full lines, the relative position of orifices 27 and 28 relatively to passages 16 and 29 when shaft 17 is in open position (Figure 1). At that time passages 32 and 33, shown in dotted lines, are out of alignment with orifices 30 and 31.

Figure 4 shows the position of the various operating elements when shaft 17 is turned into closed position, orifices 27 and 28 (dotted lines) being out of line with passages 16 and 29, while passages 32 and 33 (full lines) are in alignment with orifices 30 and 31.

The form of carburetor represented in Figures 5 and 6 differs from the one already described only in that mixing chamber 5 is horizontal rather than vertical. This carburetor assembly functions substantially in the same manner as the one illustrated in Figures 1 to 4.

In practice, it is found that the mixture entering the main mixing chamber through passage 16 arrives under considerable velocity and that, unless the discharge end of passage 16 be positioned along a plane of symmetry bisecting elements 36, 37 and 38, the mixture is not evenly distributed among the cylinders.

In the claims that follow the term a "conduit system" is meant to include elements 16, 15 and 29.

What I claim is:—

1. In combination with a carburetor provided with a main nozzle, a main mixing chamber and a throttle valve controlling said mixing chamber, an auxiliary carburetor assembly comprising a chamber, passages communicating at opposite extremities with said chamber and with said main mixing chamber at points positioned on opposite sides of said throttle valve when the latter is in closed position, said chamber communicating with the atmosphere, means operative by the depression in said main mixing chamber to aspirate fuel into said chamber of said auxiliary carburetor assembly, and a valve assembly operative to control communication between said passages and said chamber, said chamber having additional communication to the atmosphere comprising a passage positioned to communicate at one extremity with the atmosphere and at its other extremity with said chamber via said valve assembly.

2. In combination with a main carburetor assembly including a main nozzle, a main mixing chamber, an auxiliary nozzle, an auxiliary mixing chamber communicating with said main mixing chamber, and a throttle valve simultaneously controlling said main and auxiliary mixing chambers, an auxiliary carburetor assembly comprising a chamber,

- passages communicating at opposite extremities with said chamber and with said main mixing chamber at points situated on opposite sides of said throttle valve when the latter is in closed position, said chamber communicating with the atmosphere, means operative by the depression in said main mixing chamber to aspirate fuel into said chamber of said auxiliary carburetor assembly, 5 a valve assembly operative to control communication between said passages and said chamber, said chamber having additional communication to the atmosphere comprising a passage positioned to communicate at one extremity with the atmosphere and at its other extremity with said chamber via said valve assembly. 10
3. In combination with a main carburetor assembly including a constant level chamber, 20 a main nozzle provided with fuel from said constant level chamber, a main mixing chamber positioned to receive fuel discharged from said main nozzle, and a throttle valve positioned inside said main mixing chamber, a conduit system having a pair of terminal orifices positioned to communicate with said main mixing chamber at points situated on opposite sides of said throttle valve when the latter is in closed position, a passage communicating at opposite extremities with the atmosphere and with said conduit system, a well communicating with the atmosphere and supplied with fuel from said constant level chamber, a tube communicating at opposite extremities with said conduit system and with the fuel contained in said well, a second passage positioned to communicate at opposite extremities with the atmosphere and with said conduit system, and a valve operative 30 to simultaneously control communication between said second passage and said conduit system, and between said main mixing chamber and portions of said conduit system. 35
4. In combination with a main carburetor assembly including a constant level chamber, 45 a main nozzle provided with fuel from said constant level chamber, a main mixing chamber positioned to receive fuel discharged from said main nozzle, and a throttle valve positioned inside said main mixing chamber, a conduit system having a pair of terminal orifices positioned to communicate with said main mixing chamber at points situated on opposite sides of said throttle valve when the latter is in closed position, a passage communicating at opposite extremities with the atmosphere and with said conduit system, a well communicating with the atmosphere and supplied with fuel from said constant level 50 chamber, a tube communicating at opposite extremities with said conduit system and with the fuel contained in said well, a second passage positioned to communicate at opposite extremities with the atmosphere and with said conduit system, and a valve operative 55 to simultaneously control communication between said second passage and said conduit system, and between said main mixing chamber and portions of said conduit system. 60
5. In combination with a main carburetor assembly including a constant level chamber, a main nozzle communicating with said constant level chamber, a main mixing chamber positioned to receive fuel discharged from said nozzle, and a throttle valve positioned inside said main mixing chamber, an auxiliary carburetor assembly comprising a well communicating at opposite extremities with the atmosphere and with said constant level chamber, a tube extending into said well and having a free extremity positioned to lie below the level of fuel contained in the latter, a chamber communicating with said tube, a first passage extending from said chamber to a point in the wall of said main mixing chamber situated upstreamward with relation to said throttle valve, a second passage extending from said chamber to a point in the wall of said main mixing chamber situated downstreamward with relation to said throttle valve when the latter is in closed position, a third passage communicating at opposite extremities with the atmosphere and with said chamber, a disc mounted inside said chamber and having orifices formed therethrough positioned to move across said first and second passages at the points where the latter communicate with said chamber, and means for rotating said disc. 70
6. A structure as defined in claim 5 in combination with an auxiliary nozzle, and an auxiliary mixing chamber communicating with said nozzle and with said main mixing chamber. 80
7. A structure as defined in claim 5 in combination with a second disc mounted inside said chamber and having an orifice formed therein positioned to move across said third passage, said second disc being rotatable by 90 said last named means. 95
8. A structure as defined in claim 5 in combination with a second disc mounted inside said chamber and having an orifice formed therein positioned to move across said third passage, said second disc being rotatable by 100 said last named means, and a spring tending to move said discs apart. 110
- In testimony whereof I affix my signature.
M. MENNESSON. 120
